UNITED STATES PATENT OFFICE.

JAMES HOWELL, OF LANCASTER, OHIO, ASSIGNOR OF ONE-HALF TO JOHN H. LITTRELL, OF SAME PLACE.

WRENCH.

SPECIFICATION forming part of Letters Patent No. 674,767, dated May 21, 1901.

Application filed February 26, 1901. Serial No. 48,962. (No model.)

To all whom it may concern:

Be it known that I, JAMES HOWELL, a citizen of the United States, residing at Lancaster, in the county of Fairfield and State of Ohio, have invented new and useful Improvements in Wrenches, of which the following is a specification.

The invention relates to wrenches, and to that class having an adjustable jaw, and its object is to improve the adjusting and locking devices of the adjustable jaw.

The invention consists in the construction herein described and pointed out.

In the accompanying drawings, Figure 1 is a side elevation of the improved wrench. Fig. 2 is a plan. Fig. 3 is a section on line 3 3 of Fig. 2. Fig. 4 is a perspective of a locking-plate.

Numeral 1 denotes a handle of any usual construction, and 2 is a fixed jaw made integral, in the present instance, with a portion of the handle.

3 denotes an adjustable jaw. It is provided with a shank 4, whereby it is held in proper relation to the fixed jaw. This shank, which has less thickness than the jaws, is situated in a slot 5, formed in the fixed jaw, and is movable therethrough to vary the distance between the gripping-faces of the jaws.

6 indicates a shoulder at the junction of the shank and jaw 3, and 7 is a shoulder on the fixed jaw, acting as a stop against the rear end of jaw 3.

8 denotes a slotted locking-plate fitting upon the outside of the fixed jaw and embracing the jaw-shank, as shown.

9 indicates a tooth at the forward end of the slot, adapted to engage any one of the notches or slots 10 of a rack formed on the front edge of the shank 4. This tooth or holding-pawl 9 is beveled on its outer side to give it a drawing action when crowded between two of the rack-teeth. This provides for a nicer adjustment of the jaws than would be otherwise practicable.

The plate when suitably engaged with the shank under the particular desired adjustment of the movable jaw is fixed in position by a set-screw 11, working in a suitably-threaded socket in the tool.

The jaws are made long and pointed to facilitate the use of the wrench in corners and contracted spaces. One jaw is serrated to insure a good holding grip and the other, pref-

erably the movable jaw, is provided with a smooth face to favor intentional release.

The shoulder 7 prevents the tilting of the movable jaw and decreases the leverage between the movable jaw and its shank.

The locking-plate is easily manipulated and at a considerable distance from the jaws. It has a secure and positive engagement with the jaw-rack and is itself firmly held by the thumb-screw, which is subjected to no strain.

Obviously the gripping capacity of the wrench has a wide range and the construction is characterized by simplicity, durability, ease of adjustment, and general efficiency.

I am aware that a wrench having a jaw provided with a shank transversely adjustable in a slot in the shank of the coacting jaw, said transversely adjustable jaw being serrated on its rear edge and engaged by a spring-actuated serrated plate, has been proposed and that a similar plate or cotter has also been held in operative position by means of a screw situated in the handle lengthwise thereof. By my improvement the transverse shank is notched or serrated on its front edge and combined with a plate situated lengthwise the tool and fixed to it opposite the notched edge of the transverse shank. Preferably a single tooth is employed to engage either one of the notches of the shank at will. Springs are dispensed with and the article is simplified in construction, the locking parts being at all times visible and easily accessible. Any tendency of the jaws to open in use is directly resisted by the locking-plate acting on the front edge of the jaw-shank.

Having thus described my invention, what I claim as new, and desire to secure by Letters Patent, is—

In a wrench, a movable jaw provided with a shank notched on its forward edge, in combination with a plate having a tooth to engage the notches of the shank, and a device for locking the plate to the tool, said device consisting of a thumb-screw passing through the plate and engaging the shank of the opposing jaw.

In testimony whereof I have hereunto set my hand in presence of two subscribing witnesses.

JAMES HOWELL.
